LOCKING DEVICE

Ewing L. Sharp, Los Angeles, Calif., assignor to
Josephson & Sharp Manufacturing Co., Glen-
dale, Calif., a copartnership

Application May 12, 1944, Serial No. 535,246

3 Claims. (Cl. 292—36)

This invention relates to improvements in devices for interlocking various types of apparatus, but it is primarily intended to lock covers on ammunition boxes and subsequently to lock such boxes in position within receptacles provided for receiving the boxes.

It is the object of my invention to provide a simple and inexpensive device of the character referred to by means of which such installing and locking operations may be greatly facilitated and expedited. To this end, the invention resides in the combinations illustrated in the appended drawing and hereinafter fully described.

In the drawing:

Fig. 1 is a plan view of a device embodying the invention;

Fig. 2 is a cross sectional end view taken substantially through the center of Fig. 1 from left to right; and

Fig. 3 is a detail view, partly in section, of a portion of Fig. 1.

The structure of the invention, in the form illustrated in the drawing comprises a tubular housing 1, within the ends of which a pair of plungers 2 are seated to slide. Because both ends of the device may be and preferably are exactly alike, only one end thereof is described in detail.

A flange 4 extends laterally from the housing, and this flange supports pivots 5, 6, on which operating levers 7, 8 are mounted to swing. These levers terminate at the top in finger pieces, or wings 7^a, 8^a for convenience in operating the levers, as will be fully described presently. Rods 3 are rigidly fastened within the plungers 2 and their inner ends are bent to form loops 3^a, which ride on studs 9 of the levers.

It is noticed that the levers pass through slots 1^a of the tubular housing, and that they have sufficient freedom of movement therein to retract the plungers until their outer ends become flush with the ends of the housings or even withdrawn within the housing. Springs 10 are placed behind the plungers to maintain the latter normally projected, and it is noticed that the inner ends of these springs abut inwardly directed stops 11 of the housing.

A resilient, U-shaped member 15 is fastened to the tops of the pivots 5, 6, and this member extends under the wings of the levers 7, 8. The ends of this extended portion of the member are shown upwardly curved to form stops 15^a, 15^b to limit outward swinging movement of the levers.

As stated in the preamble to this specification, the device of my invention is primarily designed to lock covers in position on ammunition boxes

and subsequently to lock such boxes within receptacles provided for this purpose. In order to describe such combination, I show a cover comprising a flat base 16, from which rise folded end pieces 16^a, 16^b, having perforations 16^c for registration with the plungers 2, and also in dotted outline portions of such sheet metal box 17. The side walls of this box are made with perforations for registration with the perforations of the cover and the plungers 2.

The tubular housing is shown made with lugs 1^b, 1^c, by means of which it is fastened to the base 16 of the cover. Two such housings are shown mounted on the cover base and so positioned thereon that the ends of the plungers ride within the cover perforations. When it is desired to mount the cover on the box, it is first required to grip the wings 7^a, 8^a between the fingers of both hands and to apply sufficient pressure thereagainst to swing the levers until the ends of the plungers recede within the housings. The cover may then be lowered to cause the folded ends thereof to straddle the box walls and the movement is continued until the perforations of the two parts reach a position of registration. When thereupon the pressure against the wings is relieved, it is found that the plunger ends by the springs 10 are forced outward through the perforations until flush or nearly flush with the outer surfaces of the cover ends, thereby to lock the cover in position on the box, substantially as indicated in Fig. 2.

Ammunition boxes, such as herein discussed, are designed for storage and use in airplanes, and receptacles are provided in such planes, within which the boxes are tightly locked in position. Each receptacle is provided with perforations for registration with the aligned box and cover perforations, when the box is seated therein. The box is thereupon locked in position within the receptacle by merely depressing the free end of the resilient member 15 until the stops 15^a, 15^b thereof sink below the bottom edges of the wings, substantially as indicated at 8, 8^a at the bottom of Fig. 2. The levers 7, 8 and plungers 2 are in this manner released and by the springs 10 forced outward to cause the ends of the plungers to seat in the perforations of the receptacles and so securely to lock the box in position therein.

I am aware that other, plunger fitted devices have been introduced for similar purposes, but such devices as have come to my notice are slow and cumbersome to operate, principally because each plunger must be separately operated for

successive positioning in three sets of notches of the plunger housing. But in the device of my invention, it is merely required to grip and to press together the wings of the levers to seat the cover and then to depress the members 15 after the box is seated in its receptacle.

It may be found advantageous to provide a positive stop for the downward movement of the member 15. Illustrative of such stop means, a lip 15^c is shown punched out of the material thereof and bent downward to contact the flange 4 when the member is depressed. It may also be found advisable to provide openings 1^c through the plunger housing for insertion of the ends of the studs 9 through the eyes of the plunger rods 3 into the levers 1, 8. A few light taps of a hammer on a center punch applied to the ends of the studs will suffice to rivet the latter securely in position.

While the structure above described is illustrative of means adapted to such simple, convenient and efficient operation, I do not wish to be limited to the precise structural combinations and arrangements of parts, but reserve the right to embody modifications within the scope of the claims hereto appended.

It was above stated that the rods 3 are rigidly secured within the plungers 2 and, while this of course is essential, it is preferable to afford the rods some freedom of oscillation within the plungers to adjust themselves to the swinging movement of the levers 1, 8. To this end, the rods are shown made with outer loops 3^b, seated within slots of the plungers, and pins 17 of the plungers serve as pivots for the rods. Because these pins at all times remain seated within the housings, it is seen that they cannot become dislodged and so maintain the rods firmly in position.

I claim:

1. In a locking device, a tubular housing, plungers slidable within the ends of the housing, means for controlling said plungers comprising, a pair of levers pivotally hung on the housing, elements interconnecting said levers with the said plungers, resilient means urging the plungers apart, and a member engaging said levers to check outward movement of the levers and plungers, the levers being manually operable simultaneously to retract the plungers against the tension of said resilient means, the said member being manually movable to release the levers and plungers for outward movement.
- 15 2. In a locking device, a tubular housing, plungers axially slidable within the ends of said housing, a pair of levers pivotally hung on the housing, elements interconnecting the levers with the plungers, resilient means urging the plungers outward, and a resilient plate on the housing engaging said levers to check outward movement thereof, said plate being manually deflectable to release the levers for outward movement.
- 20 3. A locking device comprising a housing, plungers axially slidable within the ends of said housing, levers hung on the housing between said plungers, elements interconnecting said levers and plungers, the levers being manually operable to draw the plungers inward, resilient means urging the levers and plungers outward, and a resilient member on the housing having flanges engaging said levers to check outward movement thereof, said member being manually depressible to release the levers and plungers for outward movement.
